UNITED STATES PATENT OFFICE

WILLIS HAWSON LEACOCK AND JONTHON LLOYD SNYDER, OF LINCOLN, NEBRASKA

SASH BAR

Application filed February 21, 1929. Serial No. 341,719.

This invention relates to sash bars designed to be used as window mullions or corner posts. The general object of the present invention is to so construct the bar that it is adapted to be used for engagement with panes of glass disposed either in the same plane or in various angular relations to thereby permit the bar to be used as a mullion, corner post, reverse corner post or a three-way corner post.

A further object is to provide a bar of such construction that when the parts are assembled a firm, rigid, resilient and durable joint will be provided between adjacent or vertical abutting edges of window panes and particularly the heavy plate glass panes required in store fronts or show windows.

Another object is to so construct the sash bar that the parts may be readily and easily assembled to effect connection of panes or plates in the same plane or adjacent or in angular relations or to connect two plates or panes disposed in the same plane with a third pane or plate having angular relation to the other two panes.

Another object is to provide a sash bar which is so constructed as to afford a strong reinforcement of the window to thus cause the window to successfully withstand pressure and at the same time provide means for holding the adjoining plates or panes in a resilient and flexible grip.

Another object is to provide a construction of this character which is storm-proof and leak-proof and in which the pane clamping members may be caused to resiliently grip the panes and hold the margins of the panes in firm engagement with the sash bar.

Other objects will appear in the course of the following description.

Our invention is illustrated in the accompanying drawings, wherein:—

Figure 1 is a face view of a window having our improved sash bar applied thereto;

Figure 2 is a section on the line 2—2 of Figure 1;

Figure 3 is a like view to Figure 2, but showing a different position of the panes;

Figure 4 is a like view to Figures 2 and 3 but showing a different adjustment of the panes;

Figure 5 is a fragmentary section through one of the pane clamping members and a portion of the pane before the clamping member has been closed;

Figure 6 is a transverse sectional view through a modified form of sash bar;

Figure 7 is a fragmentary section through one of the screws and this terminal;

Figure 8 is a top plan view of Figure 7;

Figure 9 is a perspective view of one of the reinforcing members.

Referring to the drawings, in Figure 2 it will be seen that our sash bar comprises the stiffener 10 which is preferably made of steel and is hollow and may have any desired general shape either circular in cross section or non-circular. This stiffener is formed to provide two closely adjacent faces 11 which are slightly concave separated by a medially disposed portion 12. The opposite portion of this stiffener is formed with a flat face 13.

Adapted to extend through the stiffener and specifically through these faces 12 and 13 is a bolt 14 having a head 15. Disposed upon the bolt just inward of the head is a copper strip 16 bent to form a flat intermediate portion and two laterally curved wings 17. The bolt 14 passes through the medial portion and between the two wings and the head 15 of the bolt is so formed as to bear against these two wings. In other words it is provided with two inwardly convergent faces for this purpose. The strip 16 is held in place upon the bolt 14 by means of a lock nut 18. A nut 19 engages the outer end of the bolt and bears against the face 13.

The plates or panes 20 of glass or other ma-

5 terial designed to be held in place are gripped on their margins by the somewhat resilient or yieldable copper clamping members 21. These are approximately circular in cross section but are longitudinally slotted for their entire length and have inwardly extending flanges 22 defining said slit. These flanges are initially as shown in Figure 4 disposed at a slight angle to each other so that when the clamping member 21 is forced upon the margin of a window pane or plate, these flanges will be forced inward into parallel relation and will firmly engage flat against the opposite marginal faces of the pane or plate.

15 The wings 17 of the strips 16 conform in shape to the circular clamping members 21 and the faces 11 are also curved so as to conform to the circular shape of the clamping members 21. Thus it follows that when the
20 nut 13 is turned upward, the bolt 14 will be drawn inward forcing the strip 16 and its wing 17 firmly against the clamping members and forcing these clamping members to a firm seat against the concave faces 11 of the reinforcing stiffener 10.

25 Preferably a covering strip 23 will be extended over the heads 15 of all of the bolts 14, this covering strip having inwardly converging flanges engaged by the side faces of the
30 heads, thus making a water-tight joint with the wings 17 and preventing any inlet of water around the heads of the bolts and at the same time providing an attractive finish for the sash bar, this strip being preferably made of copper.

35 As shown in Figures 2 to 4 the panes 20
may be disposed either in alinement with each
other or at right angles to each other and at
an acute angle to the bolts 14 or as in Figure
40 4 at right angles to each other, but disposed
reversely to the arrangement shown in Figure
3 or at obtuse angles to the bolt 14. Thus it
will be seen that the clamping members 21
may be readily rotated into a large number
45 of angular positions with relation to each
other and thus these parts may be employed
when assembled in various combinations and
positions with equal facility so that the sash
bar may form a mullion, a corner post, a re-
verse corner post or a combination mullion
50 and corner post as desired.

In Figure 6 is illustrated a slight modification of the structure shown in Figure 2 by which three panes of glass 20 may be engaged with each other in any desired angular relation. In this construction, two stiffening members 10 are used, each having two bolts designated 14, these bolts extending through the stiffening members as before described and being disposed at an obtuse angle with relation to each other. There are three clamping members 21 which are used, these clamping members being constructed of copper as heretofore described and associated with two of these clamping members is the copper strip

16 as heretofore referred to. Passing through the middle of the strip 16 is a bolt 14^a carrying the nut 18 as heretofore described. Each of the bolts 14^a and 14^b has screw-threaded engagement with an annular member 24 having a screw-threaded shank or socket 25. These annular members 24 are disposed in alignment with each other and a rivet 26 or equivalent member acts as a pivot for these three annular members 24.

The parts are assembled as illustrated in Figure 6 with the three plates of glass disposed so that two of the plates are in alignment with each other and the other plate extends at right angles to the other two plates and then by tightening up on the bolts 14^a, the stiffeners 10 are forced toward the center rivet 26 and the bolt 14^b is drawn inward and thus the three clamps 21 are compressed upon the panes and urged toward each other. 80 85

It will be seen that in all of the forms disclosed, one or more stiffening members 10 are used and that these provide curved seats having substantial areas for engagement with at least two of the more or less cylindrical pane 90 clamps 21 and that these pane clamps are also engaged by the curved wings of the strip 16. Thus the clamps are not only held in place against any possible detachment, but they are compressed upon the glass of the panes. The 95 stiffening bar extends vertically and forms a supporting post as it were and a reinforce against which the two panes bear. It will likewise be obvious with this construction the panes may be shifted into any desired angular 100 relation within the range of the mechanism and that it is possible to dispose three panes into angular relation, either the angular relation shown in Figure 6 where one pane is disposed at right angles to the other two or with two of the panes disposed in angular 105 relation to each other as well as to the third or all of the panes disposed radially but at equal angles to each other. It will, therefore, be seen that this structure is capable of many 110 different combinations and arrangements fitting it for a large number of different situations.

The structure is so reinforced as to successfully withstand severe lateral pressure and yet secures a union that holds the joining panes or plates in a resilient flexible grip. It will further be noted that the pressure against the margins of the panes is distributed by the flanges of the clamping members 21. 120

We claim:

We claim:—
1. A sash bar comprising a plurality of pane gripping members circular in cross section, a bolt passing between the members and having a head at one end, an outer metal strip 125 extending parallel to the members and bearing thereagainst and formed on its lateral margins to conform to and extend over said members, and a stiffening and supporting element disposed between the gripping mem- 130

bers and having transversely concave seats formed thereon to receive the gripping members and through which stiffening and supporting member said bolt passes, the gripping members being axially rotatable within said seats.

2. A sash bar comprising a stiffening and supporting member formed with two concave seats, a bolt passing through the stiffening member between said seats and having a head, a pair of sash gripping members circular in cross section and disposed upon said seats and between which the bolt passes, and a metallic strip through the middle of which the bolt passes and having lateral wings curved to fit against and extending partially around the sash gripping members and opposed to said seats, the gripping members being rotatively adjustable in said seats.

10 3. A sash bar including a plate clamping member having a longitudinally extending opening to receive the margin of a plate, and means for supporting said member and permitting a rotative adjustment thereof including a stiffening bar having a transversely concave seat against which the clamp is rotatably disposed, a clamping plate opposed to the stiffening member and having a transversely concave seat bearing against the face of said clamp, and means whereby the stiffening member and the clamping member may be urged toward each other.

4. A sash bar including two pane clamping members cylindrical in cross section and having a longitudinal opening for the reception of the margin of the sash, a stiffening member having a pair of transversely concave seats disposed in angular relation to each other, the seats being transversely concave to conform to the curvature of the clamping members, a bolt passing through the stiffening member between said seats and having a head at its outer end, a strip through which the bolt passes having a pair of outwardly curved wings conforming to the curvature of the clamping members, the head of the bolt being beveled against said wings and means on the inner end of said bolt and bearing against the stiffening member whereby the bolt may be tightened to cause the compression of the clamping members.

5. A sash bar of the character described, comprising a hollow stiffening member having a pair of transversely concave seats disposed one on each side of a medial plane, a bolt passing through the stiffening member between said seats and having a head at one end and a nut at the other, the nut bearing against the stiffening member, a strip through which the bolt passes and against which the head of the bolt bears, the strip having outwardly curved wings, the wings forming seats confronting said seats formed in the stiffening member and the head of the bolt being beveled against said wings, and

pane clamping members circular in cross section disposed one on each side of the bolt and rotatively adjustable in said seats, each of said members having a longitudinal opening through which the margin of the pane is inserted and the opening being defined by inwardly extending flanges.

6. A sash bar including a stiffening element formed with two curved seats on each side of the medial plane, a bolt passing longitudinally through the stiffening element, sash pane clamping members each circular in cross section and rotatably adjustable in said seats and having a slot for the reception of the pane and disposed against said seats, and members with which the bolt operatively engages and adapted to be forced against the pane clamping members to compress the latter when the bolt is retracted, and a nut bearing against the stiffening member and engaging said bolt whereby it may be retracted.

7. A sash bar including a bolt having a head, a stiffening member formed with a seat, a metallic strip engaged by the head of the bolt and formed with a seat, a circular pane clamping member rotatively disposed between said seats and adapted to embrace the margin of the pane, means whereby the bolt may be tightened and the strip may be urged toward the stiffening member, and a covering strip having inwardly turned flanges, the strip covering the head of the bolt and the inwardly turned flanges extending between the head of the bolt and said first-named strip and conforming in curvature thereto.

8. In a structure of the character described, a pair of window pane clamping members, bolts extending between said clamping members, a metallic strip carried by said bolts and having outwardly curved wings engaging against said clamping members, each of the bolts being provided with a head disposed between said wings, a covering strip extending parallel to the length of the first named strip and extending over the heads of the bolts and having inwardly turned flanges disposed against the heads of the bolts and said wings, a member against which said clamping members are abutted, and means for retracting the bolts.

9. A sash bar including a pair of stiffening members; each formed with a concavely curved longitudinally extending seat on each side of the middle of the stiffening member, the stiffening members being disposed in an angular relation to each other, bolts extending through the stiffening members, the bolts intersecting each other beyond the stiffening members, bolt sections extending out at an angle to the first named bolts and with which the first named bolts are pivotally connected, the bolt section having a head, a metallic strip through which said bolt section passes and having oppositely extending curved wings confronting the adjacent seats of the

two stiffening members, and pane clamping members disposed between said strip and between the wings of said strip and the adjacent seats on the stiffening members and adapted to be compressed between the wings of said strip and said stiffening members when the bolts are tightened.

In testimony whereof we hereunto affix our signatures.
